CHARLES GRAY,
BY George J. Mager,
HIS ATTORNEY.

UNITED STATES PATENT OFFICE

2,443,821

SHARPENING DEVICE

Charles Gray, St. Louis, Mo.

Application October 30, 1946, Serial No. 706,775

4 Claims. (Cl. 51—214)

1

The present invention relates to an improved device particularly adapted to more efficiently sharpen or hone the cutting edges of cutlery, especially kitchen and butcher cutlery.

As is well known, most carving knives, butcher knives, skinning and paring knives in their original state have their cutting edges convexly contoured. That is, the contour of the cutting edge from point to handle, when viewed in side elevation, is convex. Continued usage and repeated sharpening with conventional contrivances eventually result in a cutting edge concavely contoured along that region thereof which has the greatest utility.

In other words, conventional sharpeners tend to wear away a region of the blade between the handle of the knife and the point thereof in such manner that the original convex cutting edge is deformed and gradually becomes concave or reverse curved.

One of the objects of the present invention is to overcome this disadvantage by the provision on one face thereof of an arcuately formed edge-sharpening cavity whose curvature approximates that of the original convex cutting edge of the blade, so that manual reciprocation of said blade within said cavity will automatically preserve the convexity of said cutting edge.

Another object of the invention is to provide a beveled guide arrangement facilitating the insertion of cutting edges to be sharpened.

A further object is to provide a second arcuately formed edge-sharpening cavity on the opposite face of the device whose curvature may approximate that of a worn or deformed cutting edge, so that manual reciprocation of the blade within said cavity will automatically safeguard the cutting edge against further deformation.

A feature of the invention resulting from the arcuately formed edge-sharpening cavities resides in the ability, requiring little or no skill, to maintain a substantial portion of the cutting edge in contact with the stone during manual reciprocation of the blade in sharpening operations.

It is also an object of the invention to provide a sharpener whose complementary abrasive elements are encased and supported by a pair of complementary metal members in such manner that, while the edge-sharpening cavities are exposed from end to end, said abrasive elements are bodily maintained in rigid alignment.

The complete device comprises two identical abrasive elements or whetstones and two identical casing members. A compound bevel is formed along two longitudinal margins of each stone. A

2

recess is also formed in one side of each stone near one end thereof. Each casing member is provided with a large opening in its body portion, a pair of integral flanges, and an integral extension or tongue portion of predetermined length and width.

As will appear, when these four elements are assembled, there results a novel, compact, and efficient device for use in sharpening knives and the like, the abrasive components of which are protected and partially encased in metal, albeit the sharpening cavities are exposed throughout their lengths.

Additional features and advantages will be referred to in the description to follow, reference being had to the accompanying drawing in which the preferred form of the invention is illustrated.

In said drawing:

Fig. 1 is a front elevational view of the invention;

Fig. 2 is a right side elevational view thereof;

Fig. 3 is an enlarged central vertical sectional view taken on the line 3—3 of Fig. 2;

Fig. 4 is an enlarged horizontal sectional view taken on the line 4—4 of Fig. 2;

Fig. 5 is a similar view on the line 5—5 of Fig. 2;

Fig. 6 is a side elevational view of one of the abrasive elements, per se.

30 The assembled sharpening device is indicated as a whole by the numeral 10. It is seen to comprise two similar pairs of complementary elements, including a pair of stones or abrasive members 11, and a pair of casing or stone-supporting members 12, the latter being of metal.

35 As particularly portrayed in Figs. 4, 5 and 6, each abrasive member 11 is preferably of generally rectangular horizontal cross section throughout its length, that is to say, from its flat end 13 to its flat end 14.

40 One side 15 of each abrasive member 11 is flat throughout its length, except that adjacent the end 14 there is formed therein a recessed portion 16.

45 As shown in the drawing, each recess 16 is perpendicularly disposed relative the ends 13 and 14 of said abrasive member and is of elongated contour, the width thereof being calculated to snugly receive an extension of one of said casing members 12, as will appear.

The opposite side 17 of each abrasive member is likewise flat throughout its length, except that a compound bevel portion is provided along its opposite margins, each said bevel portion extending from end to end of the member 11.

Each compound bevel portion includes a first portion 18 angularly formed relative the flat side 17, and a second portion 19 angularly disposed both relative said portion 18 and the adjacent face portion 20 or 21 of said member 11.

As best seen in Fig. 6, the face portion 20 of each abrasive member is convexly contoured, while the face portion 21 is concavely contoured. Obviously, as illustrated, the oppositely disposed bevel portions 18 and 19 are necessarily analogous in longitudinal contour.

It should now be apparent that a pair of abrasive elements 11 placed in contiguous relation, with their sides 17 innermost, and their end and face portions in mutual alignment, will provide a convex blade-receiving cavity 22 as well as a concave blade-receiving cavity 23.

The complementary pair of casing members 12, previously referred to, constitutes the means whereby the pair of abrasive members is rigidly maintained in proper alignment.

Each casing member 12 includes a flat side or body portion 24, whose lateral margins are bent at right angles thereto to provide flanges 25 and 26. The flange 25 is convexly curved so as to be engageable with the face portion 20 of the abrasive element 11. The flange 26 is concavely curved so as to be engageable with the face portion 21 of said abrasive element.

As best seen in Fig. 2, a relatively large opening 27 is formed in the body portion 24 of each casing member 12 to provide horizontal edges 28 for a purpose to be explained.

Each casing member 12 is also provided with an integral, relatively long extension or tongue portion 29 whose width coincides with, or is slightly less than, that of a recess 16.

The details of the assembled device are best portrayed in the vertical sectional view of Fig. 3, and the horizontal sectional view of Fig. 5. It is seen that the tongue portion or extension 29 of one casing member 12 is of a length predetermined to span the ends 13 and 14 of a pair of elements 11, then to extend to and engage about an edge 28 of the other casing member with its terminal portion entering the recess 16 of the adjacent abrasive member.

Similarly, the extension 29 of the second casing member spans the opposite ends 13 and 14 of the pair of elements 11, then extends to and engages about an edge 28 of the first casing member with its terminal portion entering the recess 16 of the adjacent abrasive member.

It is thus seen that the two casing members are interlocked at opposite points about said abrasive members in a manner adapted to maintain the latter in rigid, aligned, and contiguous relation.

It should now be obvious that with the novel arrangement portrayed, a compact, rigid, and efficient sharpening device is provided which, especially from a manufacturing standpoint, is extremely simple to produce in quantities. It is composed of a pair of identical abrasive elements 11 and a pair of identical casings 12, the latter being interlocked to support and rigidly maintain the former in proper position.

In the assembled device, the recesses 16 of the elements 11 are oppositely disposed, as are the terminal portions 30 of the extensions 29.

For purposes of ready identification, the spanning portion of the extension 29 which is disposed right-angularly to the body portion 24 of each casing is indicated by the numeral 31; that portion thereof which is disposed right-angularly

to the spanning portion is indicated by the numeral 32; the portion thereof which engages the edge 28 of the complementary casing is indicated by the numeral 33.

5 In use, the advantages inherent in the present invention are at once apparent. The concave cavity 23 lends itself readily to sharpening convexly contoured cutting edges of cutlery from end to end, simultaneously obviating their deformation. The bevels 19 are provided to facilitate insertion of blades.

The convex cavity 22 lends itself readily to sharpening cutlery whose concavely contoured cutting edges are the result of prior sharpening operations in which devices other than the present one were employed, as well as to cutlery wherein a concave edge is desired.

Whereas the preferred embodiment of the invention has been illustrated and described, modifications regarding the degree of curvature and other details may be had without departure from the spirit of the invention.

What is claimed is:

1. In a sharpening device of the character described, a pair of similar opposed abrasive members, a pair of metal casing members about said abrasive members to maintain them in contiguous aligned relation, a convex longitudinal face and a concave longitudinal face formed on each abrasive member, a compound bevel portion along each longitudinal margin of the opposed flat sides of each abrasive member, the first pair of opposed compound bevel portions forming a convexly contoured sharpening cavity centrally of the convex faces, and the second pair of opposed compound bevel portions forming a concavely contoured sharpening cavity centrally of the concave faces of said abrasive members.

2. A sharpening device of the character described comprising two similar whetstones and two similar metal casing members; each whetstone being of generally rectangular cross-section from end to end, each end being flat, one edge of each said whetstone being convexly contoured, the other edge being concavely contoured; one side of each stone being flat throughout except for an elongated perpendicular recess there-in formed adjacent one of said flat ends, the opposite side of each stone being flat throughout with its longitudinal marginal portions each terminating in a first beveled portion of acute angularity merging into a second beveled portion of more obtuse angularity; each casing member comprising a flat body portion, a relatively large opening therein, oppositely disposed horizontal edges provided by said opening, stone-engaging integral flanges extending right-angularly from said body portion, and an integral extension or tongue portion adapted to span the flat ends of contiguous whetstones, to thence lie against an adjacent region of the body portion of the other casing member, and to thereafter engage about one of the horizontal edges of said opening in the latter with its terminal portion entering and engaging the elongated recess of the whetstone adjacent thereto.

3. A blade sharpening device comprising a pair of similar abrasive elements and a pair of similar metal casing elements, each abrasive element including two opposed flat side portions, two opposed flat end portions, and two opposed arcuately formed edge portions, a convex longitudinally extending beveled portion along one margin of one flat side portion of each abrasive element, a concave longitudinally extending beveled portion

along the other margin of said flat side portion, each of said beveled portions extending from end to end of the abrasive element; each casing including a flanged body portion and means integral therewith adapted to cooperate with means on each abrasive element for interlocking the casings about the abrasive elements and maintaining the latter in rigid aligned contiguous relation; and a pair of opposed edge-sharpening cavities provided by the contiguous disposition of said pairs of beveled marginal portions.

4. In a sharpening device of the character described, a pair of similar abrasive members and a pair of similar casing members interlocked at opposite points about the former to maintain them in rigid contiguous aligned position relative one another, a convexly contoured edge and a concavely contoured edge included in each abrasive member, a first compound bevel portion and a second compound bevel portion on each abrasive member extending longitudinally from end to end thereof, the first bevel portion being formed along one longitudinal marginal edge of

one side of each abrasive member, the second bevel portion being formed along the other longitudinal edge of the same side of each abrasive member, and oppositely disposed blade receiving cavities formed by a pair of said first and a pair of said second bevel portions.

CHARLES GRAY.
